CLAIM

The ornamental design for a handheld computing device, as shown and described.

DESCRIPTION

FIG. 1 is a front, top perspective view of a handheld computing device showing the new design;

FIG. 2 is a front elevation view thereof;

FIG. 3 is an additional front, top perspective view thereof, with a leader line showing a partial, enlarged, cross sectional view of FIG. 3;

FIG. 4 is a rear elevation view thereof, and

FIG. 5 is rear perspective view thereof; and,
FIG. 6 is a side elevation view thereof.

The broken lines shown in the drawings illustrate portions of the handheld computing device that form no part of the claimed design.

1 Claim, 6 Drawing Sheets
